UNITED STATES PATENT OFFICE.

LOUIS LICHTENSTEIN AND CHARLES O. ROBERTSON, OF WILMINGTON, DELAWARE.

PAPER MILK BOTTLE AND CAP.

Application filed December 1, 1920. Serial No. 427,482.

To all whom it may concern:

Be it known that we, LOUIS LICHTENSTEIN and CHARLES O. ROBERTSON, citizens of the United States, residing at Wilmington, in 5 the county of New Castle, State of Delaware, have invented a new and useful Paper Milk Bottle and Cap, of which the following is a specification.

Our invention consists of a bottle of the 10 class known more particularly as a paper bottle for containing milk, the same having in its mouth a single depending flange which is integral with the neck portion of the bottle at the mouth thereof and flexible so as 15 to be pressed against the inner side of said neck by the action of a cap or stopper which is adapted to press against the inner side of said flange whereby the cap is not liable to slip out of position and off from the bottle 20 and the cap is held firmly engaged with said flange while the latter after removal of the cap remains intact for further use of the bottle, thus simplifying and reducing the expense of a bottle of the kind, provision 25 being also made for conveniently grasping the cap at its upper end for the convenient removal of the cap all as will be hereafter more fully described.

It consists finally of novel means for connecting the base or bottom of the body with the latter.

The invention is satisfactorily illustrated in the accompanying drawing, but the important instrumentalities thereof may be varied, 35 and so it is to be understood that the invention is not limited to the specific details shown and described, as long as they are within the spirit or scope of the claims.

Figures 1 and 9 represent side elevations 40 of bottles embodying our invention.

Figure 2 represents a central vertical section thereof on line 2—2 Figure 1.

Figure 3 represents a top or plan view thereof.

Figure 4 represents a horizontal section 45 of a portion on line 4—4 Figure 2.

Figure 5 represents a horizontal section of a portion on line 5—5 Figure 1, on an enlarged scale.

Figure 6 represents a perspective view of a cap or stopper embodying my invention.

Figure 7 represents a section thereof on line 7—7 Figure 6.

Figure 8 represents a vertical section of 55 the cap or stopper or upper portion of the bottle on an enlarged scale.

Figure 10 represents a horizontal section on line 10—10, Figure 9.

Similar numerals of reference indicate corresponding parts in the figures. 60

Referring to the drawings,

1 designates the body of the bottle, the same being preferably of conical shape and constructed of a piece of suitable paper formed into said shape having its side ends 65 overlapping as at 2 and united firmly by the staple-like metallic clips 3 whose legs are clinched in position, as most plainly shown in Figure 2. The paper usually employed is paraffined and so said side overlapping ends of the piece as shaped adhere. This with the clips firmly unite said ends making a tight joint of the side ends of the body of the bottle from top to bottom thereof. 75

The mouth or upper end of the body is turned inwardly and downwardly forming the depending flange 4, the overlapping ends of the body at said top forming the double flanges 5 which latter are also united by the 80 clips which are passed through the same and united by the clinched clips 3, said flange being open throughout in the vertical direction forming the open mouth of the bottle. The clips that unite the double 85 flange 5 extend in horizontal direction and so cause their legs to be in horizontal direction whereby they clinch the overlapping ends of the depending flanges 4 and of the contiguous portions of the overlapped ends of 90 the top or mouth portion of the body of the bottle in horizontal direction and so take firm hold of the parts that they clinch in what may be termed the direction of the width of the four fold thicknesses of the overlapping 95 ends of the flange 5 and contiguous portions of the body of the bottle, see Figure 4, and so most effectively closing the joints of said thicknesses, making them tight thereat, since one leg is at the side of the other and separated therefrom in horizontal direction and the legs occupy a larger space on said thicknesses in said direction. Each of the clips 100 that unite the overlapping ends of the side of the body below the top of the latter extends in vertical direction and so cause its leg to be in vertical direction, whereby they clinch said overlapping ends in vertical direction, and so take firm hold of the parts that they clinch in the vertical direction of 105 the body, and so most effectively close the joint of said ends especially as one leg is

above the other and separated therefrom, and the legs extend over a longer space in the vertical direction of the body and makes a tighter joint whereby the vertical clinch 5 is applied.

The inner walls of said flanges 4 and 5 form the seat for the closing cap or stopper 6, which is adapted to be fitted tightly in said flanges, said cap being of the form of 10 a cup composed of the side 7 and bottom 8 and constructed of suitable paper.

The bottom end of the body is turned up and inwardly forming the flange 9 producing a channel in which is received the downwardly extending rim 10 of the base 11 of the bottle, said base being also formed of suitable paper, it being seated on the top of said flange 9 and so being supported solidly thereon and connected firmly by its rim with the 20 bottom of the bottle, it being noticed that the overlapping ends 2 of the body also occupy the relative portions of said channel.

In the embodiment shown in Figures 9 and 10, the side ends of the body of the bottle are turned laterally in opposite directions and engaged with each other forming the interlocking lap joints 12 which are connected by the clinched clips 3, thus producing a fluid tight joint for said side ends. It 30 will be seen that the depending flange 4 is yielding and resilient in its nature whereby when the cup is inserted therein the side wall 7 thereof wedges in a measure with said flange and so the latter hugs said wall in a firm and tight manner which prevents leakage of the fluid at the top of the bottle and retains the cup in closed position until properly withdrawn.

The height of the side wall 7 is such that 40 its upper portion 13 projects exposed above the top edge of the bottle where it may be grasped or engaged by a suitable opener and so removed to open the bottle in a convenient and easy manner.

Attention is drawn to the fact that excepting where the ends of the flange 4 are united said flange is a single piece of material integral with the side wall of the body depending from its top bend on the mouth 50 of the bottle loosely therefrom to its bot-

tom, hence when the cap 6 which is cup shaped is inserted into said flange it has its side wall ride down the inner face of said flange and as the latter yields inwardly it is compressed flat against the inner face of the mouth portion of the bottle, see the right hand of Figure 8, and so is frictionally engaged by the cap and forms a tight joint for the latter. Then as the cap is cup shaped, while the main portion of its side wall is wedged against the side of the flange, another portion projects above the top bend of the flange so as to be grasped as has been stated, whereby the cap may be extracted without being pried out and injured so it can be reused, while the top bend of the flange remains intact and no implement to remove the cap requires to be fulcrumed on said bend.

Having thus described our invention what 70 we claim as new and desire to secure by Letters Patent, is:—

1. A paper bottle having in its mouth portion a single inturned and downturned flange which is integral with the side wall of the body of the bottle, bent from the mouth and depending from the bend to its bottom entirely free of the inner face of the said mouth portion, and a cup shape cap having its side adapted to engage frictionally with the inner side of said flange and compress it against the side of the mouth portion of the bottle.

2. A paper bottle having in its mouth portion a single inturned and downturned flange which is integral with the side wall of the body of the bottle, bent from the mouth and depending from the bend to its bottom entirely free of the inner face of said mouth portion, and a cup shape cap having its side adapted to engage frictionally with the inner side of said flange and compress it against the side of the mouth portion of the bottle, the upper portion of said side being extended upwardly above said bend.

LOUIS LICHTENSTEIN.

CHARLES O. ROBERTSON.
